[57] CLAIM

The ornamental design of a computer communicator
used to transmit language characters and numerical
signals to a computer, as shown and described.

DESCRIPTION

FIG. 1 is a top front and right side perspective view of
a computer communicator used to transmit language
characters and numerical signals to a computer showing
my new design;

FIG. 2 is a front view thereof;

FIG. 3 is a right side view thereof;

FIG. 4 is a left side view thereof;

FIG. 5 is a top plan view thereof;

FIG. 6 is a bottom plan view thereof;

FIG. 7 is a rear view thereof;

FIG. 8 is a top front and right side perspective view of a
second embodiment thereof;

FIG. 9 is a front view thereof;

FIG. 10 is a right side view thereof;

FIG. 11 is a left side view thereof;

FIG. 12 is a top plan view thereof;

FIG. 13 is a bottom plan view thereof;

FIG. 14 is a rear view thereof;

FIG. 15 is a front view of a third embodiment thereof;

FIG. 16 is a right side view thereof;

FIG. 17 is a left side view thereof;

FIG. 18 is a top plan view thereof;

FIG. 19 is a bottom plan view thereof; and,

FIG. 20 is a rear view thereof.
